UNITED STATES PATENT OFFICE.

RAYMOND V. OWEN, OF ST. LOUIS, MISSOURI, ASSIGNOR TO THE EDWIN F. GUTH COMPANY, OF ST. LOUIS, MISSOURI, A CORPORATION OF MISSOURI.

DESIGN FOR A LIGHTING-FIXTURE GLOBE OR SIMILAR ARTICLE.

Application filed July 28, 1926. Serial No. 18,517. Term of patent 14 years.

To all whom it may concern:

Be it known that I, RAYMOND V. OWEN, a citizen of the United States, residing at St. Louis, State of Missouri, have invented a new, original, and ornamental Design for Lighting-Fixture Globes or Similar Articles, of which the following is a specification, reference being had to the accompanying drawings, forming a part thereof, in which

Fig. 1 is a side elevation view of my globe, illustrating the contour thereof, the surface ornamentation being shown diagrammatically;

Fig. 2 is a bottom view of the same, the surface ornamentation also being shown diagrammatically; and

Fig. 3 is an enlarged detail view of a portion near the center of the globe, clearly illustrating the character and shape of the surface ornamentation which, in Figs. 1 and 2, is shown diagrammatically.

I claim:

The ornamental design for a lighting fixture globe or similar article, substantially as shown.

RAYMOND V. OWEN.
